UNITED STATES PATENT OFFICE.

HENRY WATERS, OF BISBEE, ARIZONA TERRITORY.

SHOEMAKER'S TELESCOPIC REPAIR OUTFIT.

SPECIFICATION forming part of Letters Patent No. 643,213, dated February 13, 1900.

Application filed June 9, 1899. Serial No. 719,872. (No model.)

To all whom it may concern:

Be it known that I, HENRY WATERS, a citizen of the United States, residing at Bisbee, in the county of Cochise and Territory of 5 Arizona, have invented certain new and useful Improvements in Shoemakers' Telescopic Repair Outfits; and I do declare the following to be a full, clear, and exact description of the invention, such as will enable others 10 skilled in the art to which it appertains to make and use the same.

My invention relates to a telescopic repair outfit or kit for shoemakers; and the object 15 is to provide a simple, convenient, and portable device of this character.

To this end the invention consists in certain features of construction and combination of parts, which will be hereinafter fully described and claimed.

20 In the drawings, Figure 1 is a side elevation, partly in section, of my improved telescopic repair-jack as it appears in use for pegged or nailed work. Fig. 2 is a similar view showing another position of the jack. 25 Fig. 3 is a similar view showing the position for trimming the sole of a shoe. Fig. 4 is a detail view of the toe-rest. Fig. 5 is a horizontal section on the broken line 5 5 of Fig. 1. Fig. 6 is a transverse section of the last on 30 the line 7 7 of Fig. 3.

In the drawings, 1 denotes the base, and 2 the tubular standard, the upper end of which is provided with a series of longitudinal dovetailed tapering ribs 3 3, which engage corresponding slots or recesses 4 4 in the encompassing sleeve 5, which has a sliding connection therewith and in which is journaled the stud-shaft 6, to the upper end of which the 35 U-shaped yoke 7 is removably secured by 40 means of the nut 8.

9 denotes an intermediate section connected to the lower end of the shaft by the knuckle-joint 10, and the lower end of said section 9 is similarly connected by the knuckle-joint 45 10' to the rod 12, the lower end of which terminates in a disk flange 13, and 14 14 de-

note transverse orifices formed in the tubular standard to receive the removable pins 15, which extend across the path of the disk flange 13 to retain the yoke in the positions shown 50 in Figs. 1, 2, and 3.

16 denotes a stud fixed in the upper end of the yoke, and it is formed with lateral lugs 17 17, which engage the shoulder 18 of the last 19 to retain the latter in place.

When it is desired to remove the last, it is turned horizontally until the lugs 17 are aligned with the vertical recesses 20 in the last and then raising it, thus permitting the last 55 to be detached from the yoke.

60 26 denotes the toe-rest, pivoted at its lower end to the upper end of the shorter member of the yoke 7.

28 denotes the hand-lever or pawl fulcrumed in the toe-rest, and 27 denotes a spring 65 which serves to hold said pawl in engagement with the yoke 7.

It will of course be understood that various changes in the form, proportion, and the minor details of construction may be resorted to 70 without departing from the spirit or sacrificing any of the advantages of this invention.

Having thus described the invention, what is claimed, and desired to be secured by Letters Patent, is—

75 In a telescopic shoe-repairing jack, the combination with the tubular standard 2 formed with the ribs 3 3 and transverse orifices 14, of the pins 15, the stud-shaft 6, the sleeve 5 formed with the longitudinal recesses 4, the 80 rod-section 9 pivoted to said shaft, and the rod 12 pivoted to said section 9 and formed with the flange 13, substantially as shown and described.

In testimony whereof I have hereunto set 85 my hand in presence of two subscribing witnesses.

HENRY WATERS.

Witnesses:

T. M. VAUGHN,
R. S. JURADO.
